DEVELOPING APPARATUS

Filed Feb. 20, 1928

UNITED STATES PATENT OFFICE

ADOLPH LANGSNER, OF CHICAGO, ILLINOIS, ASSIGNOR TO EUGENE DIETZGEN COMPANY, OF CHICAGO, ILLINOIS, A CORPORATION OF DELAWARE

DEVELOPING APPARATUS

Application filed February 20, 1928. Serial No. 255,636.

This invention relates to developing apparatus and more particularly to a cabinet type of device for developing light sensitive material such for instance as paper by the action of chemically active gases such for instance as ammonia gas.

One of the objects of my invention is to provide a very compact and effective type of apparatus for quickly and easily developing the light sensitive material without subjecting the operator to the objectionable action of the developing gas.

Still another object of my invention resides in providing a cabinet type of machine into which the light sensitive material may be manually placed by the attendant and wherein the cabinet is provided with a container for a liquid adapted to give off the developing gas such as ammonia and wherein such container is provided with a closing means adapted to be controlled from the outside of the cabinet so that when the cabinet is opened to insert or withdraw the light sensitive material, the openings in the container through which the developing gases escape may be closed before time so as to prevent the escape of gas.

Still another object of my invention resides in the novel type of shutter or closure for the container holding the liquid developing medium giving off the developing gas and the manner in which it is controlled from without the cabinet.

Yet another object of my invention resides in the arrangement of the basket or holder for the light sensitive material and the manner of suspending it above the container for the gas within the cabinet.

Still a further feature of my invention resides in the slidable shutter or blanket for enclosing the retainer tank within the cabinet which blanket, if desired, may be perforated for the passage of the developing gas therethrough and to close the openings in the liquid container in another position.

A further feature resides in the provision of a relatively flat tank for containing the liquid developing means and a flexible shutter or top for this tank adapted to open or close the top of the tank to permit the escape of the gas or shut it off completely and which tank is

made relatively shallow to permit ample room for the location and operation of a swingable basket disposed at the top of the developing cabinet and normally moved to such position whereby the developing gas when rising, comes into effective action with the light sensitive material contained in the basket and whereby the basket may be lowered to a point well below the top portion of the cabinet and to a point opposite the opening in the cabinet from which position the light sensitive material from the basket may be withdrawn.

These and other objects of my invention will be apparent from a perusal of the following specification when taken in connection with the accompanying drawing wherein:

Figure 1 is a side sectional view of the preferred form of my device; and

Figure 2 is a partial and similar sectional view showing the altered position of the closing member for the tank containing the developing liquid.

In general, the present form of my apparatus comprises a cabinet made of substantially gas-tight construction and is preferably provided intermediate its height at one end with a door through which the attendant may insert or withdraw light sensitive material such as a roll or sheet of paper into a basket or other holder contained in the cabinet. The basket is mounted in the cabinet and constructed and arranged so as to be normally projected at the very top portion of the cabinet and held there so that the developing gas within the cabinet which rises naturally to the top of the cabinet will have free access to the light sensitive material to develop it. In addition, the cabinet contains at the bottom, a relatively shallow tank extending the full length of the cabinet and of the basket and which is formed at the top to permit the escape of a suitable developing gaseous medium from the tank into the cabinet. This tank contains a connection to a point outside of the cabinet so that the tank may be filled and emptied without otherwise opening the cabinet. In addition, the cabinet contains a preferably flexible shutter or closure which extends over the top of the tank. This flexible shutter winds and un-

winds upon two oppositely disposed shafts, one located at each end of the tank and manually operable. This shutter is provided at a certain zone of its length with openings which when translated to a predetermined position over the tank permit the gas generated from the liquid therein to pass through said openings and rise upwardly into the cabinet. Another portion of this shutter or closure is wholly imperforate so that when this portion comes across and over the top of the tank, it will seal the tank against the escape of the gases therefrom. In the illustrated embodiment of my invention, the tank is provided with a perforated cover and a flexible or shiftable member is provided with correspondingly formed perforations and correspondingly formed imperforate portions which are adapted to register or not register with the perforations of the tank whereby to open and close the tank. Of course the top of the container may be formed with a single large opening in its cover, but I prefer to form the cover with a plurality of perforations as illustrated in order to get a more uniform distribution of the gas in the chamber. I also provide suitable means for turning the shafts 18 and 20 which may be of any convenient or suitable form. For instance, the shafts may be provided with manually operable handles so that the shutter may be moved in either direction or one of the shafts may be provided with a coil spring which normally winds the shaft in one direction while the other shaft is provided with a manually operable handle for unwinding the shutter against the tension of the coil spring, locking means being provided for holding the handle in such position so that the shutter may be wound from the spring controlled shaft onto the manually operable shaft and, when the handle is released, the coil spring will return the shutter to original position wound up on the shaft. Various similar arrangements are within the contemplation of my invention.

Referring now to the drawings in detail, my developing apparatus comprises a closed cabinet 2. In the present instance, this is shown as a somewhat rectangularly shaped cabinet and if formed of any type of material that will resist the corrosive action of the chemically active gas such for instance as ammonia gas. At the bottom of the cabinet, I mount a tank 4 adapted to contain liquid ammonia, for instance, which is adapted to give off ammonia gas for the developing operation. It must be apparent that any type of liquid or material for giving off chemically active gas for developing purposes is within the contemplation of my invention. This tank is adapted to be filled by means of a pipe 6 passing through the side wall of the cabinet 2 and connected to the flexible filling and discharge tube 8, the upper end of which

is held in upright position between the furcations of bracket 10. The end of this tube 8 is closed by a cork or stopper 12. As shown in the form illustrated, the tank is provided with a top 14 having along its entire length, suitable perforations 16. These perforations may be of any size and number and the top of the tank may be of foraminated material or sheet metal, suitable for resisting ammonia. The openings 16 permit the free passage of the gas evolved from liquid ammonia in the tank unless such passages 16 are closed.

One of the features of my present invention resides in providing a very compactly arranged means for closing the top of the tank so that the gas may not escape from the tank into the cabinet and the means herein provided is particularly constructed so that it can be operated from a point outside of the cabinet and so that it will not take up an unnecessary amount of room within the cabinet but on the other hand will permit of sufficient room above the tank or pan so that the basket or other holder for the light sensitive material may be conveniently lowered to a point immediately above the tank and well below the top of the cabinet so as to prevent the escape through the opening of the light sensitive material which has risen to the top of the cabinet. To this end, I provide two shafts 18 and 20, each mounted in one end of the tank and mounted in suitable bearings in either the wall of the cabinet or in the bearings supported directly within the cabinet. The shaft 18 has a gear 22 mounted thereon meshing with sprocket chain 24 and shaft 20 has a gear 26 mounted thereon also meshing with this chain. Shaft 20, in turn is provided with an operating handle 28 so that when it is turned, both of the shafts 18 and 20 will be operated through the intermediate sprocket chain 24. These shafts 18 and 20 are adapted to have wound upon them a flexible shutter or closure for the top of the tank and the arrangement is such that when the two shafts are turned in one direction, the flexible shutter will be wound from off one of the shafts onto the other and vice versa. The flexible shutter in the present instance, consists of a relatively long strip of material which is not subject to the corrosive action of the ammonia gas such for instance as felt or rubber, or in fact any other type of flexible material. This blanket or shutter or closure member 30 is formed for a portion of its length, preferably considerably longer than the length of the tank top 14, with an imperforate portion and in addition, another and equal length of the blanket 30 is provided with perforations 32 which are adapted, as shown in Figure 1, to register with the perforations 16 at the top of the tank in the position shown in Figure 1 to permit the gas to pass through both of the registering perforations and upwardly into

the cabinet. On the other hand, when the handle 28 is turned so as to wind the blanket or shutter onto the shaft 18, then the imperforate portion of the shutter 30 will be drawn over the openings 16 of the tank and will close the tank. It will be manifest that instead of having the sprocket arrangement, the same action may be accomplished by other suitable means such as by providing two handles or may be accomplished by providing a single handle on one shaft and a coil spring on the other shaft, arranged so that when the handle is operated the shaft thereof will be wound against the tension of the coil spring on the other shaft and when released, the coil spring will operate to unwind the blanket from one shaft and wind it upon the other, a suitable stop being provided for holding the handle in desired position.

By thus providing a very shallow or flat pan for the developing liquid and providing the pan with a cover of the nature described, it is evident that I am enabled to provide a relatively large space above the pan within the cabinet in which the work basket carrying the light sensitive material may be shifted so as to permit the basket to be raised and lowered to and from a position at the top of the cabinet where the developing gases collect and to and from a lowered position substantially adjacent and over the top of the pan and opposite a door or opening in the side wall of the cabinet considerably below the top of the cabinet where access may be had to the work holder for removing or inserting the light sensitive material.

It will be evident that by arranging the door considerably below the top of the cabinet, the escape of the gases which have risen to the top is more or less prevented. In the construction shown, the work holder preferably takes the form of an open mesh or wire basket 34 of any desired construction but preferably shallow, and extending the length and width of the cabinet. In the construction illustrated, I prefer to hinge or pivot one end of the basket as at 36, to the end wall of the cabinet. The other end of the basket is free but is held in raised position by means of a spring or resilient foot 38 adapted to be attached to the opposite end wall of the cabinet on the inner side thereof. Any kind of support may be used which permits the basket to swing upwardly past the stop 38 and thence to be supported in the raised position. Obviously, pushing inwardly upon this stop or by arranging a control passing through the wall and actuated from outside of the cabinet, the stop may be released or withdrawn from the basket so to permit it to be swung downwardly into the dotted line position where it may rest upon an inwardly extending ledge 40. In this position it is directly opposite a door or closure 42 hinged as at 44 to the outside of the cabinet so that by

opening this door, it is easy to insert or withdraw the light sensitive material. Means is provided for normally urging the basket upwardly into a position shown in full lines and I prefer to accomplish this by means of a spring 46 connected to the top of the basket and to the top of the cabinet. The foregoing provides a very simple means of maintaining the basket in topmost position while permitting it to be raised and lowered. It will be evident that ample room is provided for the raising and lowering of the basket and ample room is provided at the top of the cabinet for forming a sort of gas collecting chamber in which the basket is normally suspended. It will be born in mind that the ammonia gas will rise to the top of the cabinet and will collect there so that it is important that the paper to be developed should be suspended in this gaseous zone and it is also manifest that by my present arrangement of arranging the door 42 well below this gaseous zone, when the door is opened, the main body of the gas will not be permitted to escape. If desired, the door may be considerably smaller than that shown in the drawing.

Manifestly in this invention, other arrangements of the basket control, that is, the means for raising and lowering the basket, may be availed of and I do not desire to be limited to the swinging movement of the basket as any type of construction arrangement for raising and lowering the basket to uppermost and lowermost positions, are within the contemplation of my invention.

I do not claim herein the means for filling and emptying the pan from outside of the cabinet, since the same forms the subject matter of a co-pending application, Serial No. 327,242.

Having thus described my invention, what I claim as new and desire to secure by Letters Patent is:

1. In a developing apparatus for light sensitive material adapted to be developed by the action of chemically active gases, the combination of a main frame formed to provide a developing station or housing, a container in said station adapted to hold a quantity of material adapted to evolve developing gas, said housing providing a gas retaining chamber located adjacent the pan, a support for holding light sensitive material, said chamber having an opening provided with a door considerably below its top, said support being mounted in said chamber and arranged to be raised and lowered from a position in the top of said chamber to a position opposite said door, and closing means for said container.

2. In a device of the class described, the combination of an enclosing cabinet, a relatively shallow pan at the bottom of said cabinet containing a liquid adapted to give off chemically active developing gas, a closure for said pan adapted to move substantially

- in the plane of the top of said pan to open and close the same, means for controlling said closure from a point outside of said cabinet, said cabinet above said pan forming a gas collecting chamber, an opening in said cabinet, a closure therefor, said opening being disposed below said gas collecting chamber and a work holder mounted in said cabinet and shiftable from a position opposite 10 said door to a position at the top of said cabinet and in the said gas collecting chamber.
3. In a device of the class described, the combination of an enclosing cabinet, a pan in said cabinet, said pan holding liquid adapted to give off chemically active gas, said cabinet forming above said pan a chamber in which said gas collects, said cabinet having an opening for the insertion of light sensitive material into the chamber a work holder in said cabinet and arranged to hold light sensitive material to be developed by said gas, said work holder being shiftably mounted in said cabinet from loading position opposite said opening to a remote developing position within the cabinet, means to so shift the holder and a closing means for said container shiftable substantially in the plane of the top of the container, and means for operating said closing means from the outside of the cabinet.
4. In a device of the class described, the combination of an enclosing cabinet, a container therein for holding liquid adapted to give off chemically active developing gas, said container being open at its top to permit the escape of the gas therefrom, rollers disposed opposite the ends of the container, a flexible closing member overlying the top of the container and having perforate and imperforate portions, said member being wound at its opposite end upon said rollers and means for turning the rollers to shift said closing member relative to the top of said container for 40 opening and closing the latter to control the escape of the gas therefrom, and means in said cabinet for supporting light sensitive material therein.
5. In a device of the class described, the combination of an enclosing housing, a container for developing fumes having an opening therein arranged in the housing, a shaft at each end of the container and a flexible closing member overlying the opening of the container and adapted to seal the container against the escape of developing fumes when in one position, said member having one end connected to one shaft and its opposite end connected to the other shaft, and means for 50 actuating said shafts so as to shift the closing member to a second fume releasing position by winding same upon one shaft while simultaneously unwinding it from the other shaft, and vice versa.
6. In a device of the class described, the combination of an enclosing casing, a container therein for holding liquid adapted to give off chemically active developing gas, means in said cabinet for supporting light sensitive material therein, said pan having a 70 perforated top, a roller disposed in the cabinet adjacent a side of the pan and a flexible closing member having a perforated portion and an imperforate portion and wound upon said roller and means for turning the roller to permit said closing member to shift whereby to open and close the top of the pan.
7. In a device of the class described, the combination of a cabinet, a pan therein for holding liquid ammonia, said pan having a 75 top formed with perforations, a flexible closing member adapted to shift across the top of said pan, said closing band having an imperforate portion of a length sufficient to close the openings in the top of the pan, and a perforated portion, the perforations of which are adapted to register with the perforations in the top of the pan to permit the gas to rise therethrough and means operative from the outside of the cabinet for 80 actuating said closing member.
8. In a device of the class described, the combination of a cabinet, a relatively shallow pan mounted in the bottom of said cabinet and having an open top, a flat sheet-like member adapted to move across the top of said pan to close the same, means actuated from the outside of said cabinet for moving said closing member, and a work holding basket shiftably mounted in said cabinet and movable from a lowered position immediately above said closing member to a raised position at the top of said cabinet and a spring normally urging said basket to raised position, and a releasable catch for holding said basket 85 in raised position.
9. In a device of the class described, the combination of an enclosing casing, a container in the bottom of said casing for holding liquid adapted to evolve chemically active developing gases, means for closing said container, a door for said cabinet, a ledge opposite said door, a work holding basket of open construction hingedly mounted at one end of the casing adjacent the top thereof, a 90 releasable support for holding said basket in raised position, a spring normally urging said basket to such raised position and a latch opposite the door adapted to support the free end of said basket when lowered.
10. In a device of the class described, the combination of a cabinet having a door, a latch opposite the door, a basket of open construction having a pivotal connection to that wall of the cabinet opposite the door and at 95 a point above the door whereby when the basket is lowered, the free end of the basket will rest on the latch at the door and at inclined position, a spring adapted to urge the basket to raised position and a releasable de- 100

tent for holding the basket in this position, and means within the cabinet for introducing the developing gas thereinto.

11. In a device of the class described, the combination of an enclosing cabinet, a support for light sensitive material therein, a door for said cabinet, a pan in said cabinet for holding liquid adapted to give off chemically active developing gas, a shaft at each 10 end of the pan, a gear on each shaft, a driving connection between said gears, means on the outside of the cabinet for operating one of said shafts, and a pan sealing shutter connected to said shafts and adapted to be shifted by the operation of said shafts from pan sealing to pan unsealing position.

12. In a device of the class described, the combination of an enclosing cabinet, means for supporting light sensitive material therein, a relatively shallow pan at the bottom of 20 said cabinet, a shaft at each end of the pan, a gear on each shaft, a sprocket chain interconnecting the gears, a handle on one shaft mounted on the outside of the cabinet, a band 25 of non-corrosive flexible material having one end fastened to one shaft and the opposite end fastened to the other shaft, said band being of sufficient length so as to wind upon one shaft while unwinding from the other 30 shaft, said band having perforate and imperforate portions for closing the top of the pan whereby to control the escape of the developing gas.

In witness whereof, I have hereunto 35 subscribed my name.

ADOLPH LANGSNER.
